UNITED STATES PATENT OFFICE.

FRANK RADFORD AND EDWARD C. BOYER, OF DAYTON, OHIO.

DESIGN FOR A CLAMP MEMBER.

SPECIFICATION forming part of Design No. 29,921, dated January 3, 1899.

Application filed November 21, 1898. Serial No. 697,104. Term of patent 7 years.

To all whom it may concern:

Be it known that we, FRANK RADFORD and EDWARD C. BOYER, citizens of the United States, residing at Dayton, in the county of Montgomery and State of Ohio, have invented and produced a new and original Design for a Clamp Member, of which the following is a specification, reference being had to the accompanying drawings, forming part thereof, and in which like characters of reference refer to correspondingly-formed parts.

Our invention relates to a design for a clamp member for use more especially in grinding-machines.

Figure 1 is a top plan view of a clamp member embodying our new and useful design. Fig. 2 is a front elevation thereof. Fig. 3 is a sectional view thereof on line $x-x$ of Fig. 2; and Fig. 4 is a rear elevation thereof, these four views being deemed essential to fully illustrate our new and useful design.

The horizontal bar G is provided with three upward extensions II, terminating in rear-ward projections I, and two downwardly-extending arms J near the opposite ends of said bar G, while an opening K extends through the center of the length of said bar G, while on the rear side of each of the arms J is an angular projection L. Upon the front side of said bar G is a raised portion M.

The essential feature of our design for a clamp member consists of a horizontal bar having three upward rearwardly-bent extensions and two downwardly-extending arms and an opening centrally through said bar.

What we claim is—

The design for a clamp member, substantially as shown and described.

In witness whereof we have hereunto set our hands this 24th day of October, 1898.

FRANK RADFORD.
EDWARD C. BOYER.
